[57] **CLAIM**

The ornamental design for a front face segment of a vehicle tailgate, as shown and described.

DESCRIPTION

FIG. 1 is a perspective view of a front face segment of a vehicle tailgate.

FIG. 2 is a front view thereof illustrated with an inner panel rotated to a closed position.

FIG. 3 is a front view thereof with the inner panel rotated to an open position.

FIG. 4 is a left side view thereof, it will be understood that the opposite side to that shown is a substantial mirror image thereof; and,

FIG. 5 is a top view thereof.

It will be understood that the broken line illustration of the remainder of the tailgate and vehicle shown throughout the drawings is for illustrative purposes only and forms no part of the present invention. It further being understood that the bottom view is not seen during the intended use.
